SCALE FOR LIQUIDS

Marco Zanuso, Milan, Italy, assignor to
Terraillon, Annemasse, France

Filed Feb. 28, 1972, Ser. No. 230,174

Claims priority, application Switzerland Sept. 1, 1971

Term of patent 14 years

Int. Cl. D10—04

U.S. Cl. D52—10 R

Fig. 1

Fig. 2

Fig. 3

FIG. 1 is a front perspective view of a scale for liquids showing my new design, the rear being flat, plain and unornamented;

FIG. 2 is a top plan view thereof; and

FIG. 3 is a front perspective view of the liquid container/weighing pan, the rear being flat, plain and unornamented.

I claim:

The ornamental design for a scale for liquids, as shown and described.
